UNITED STATES PATENT OFFICE.

MARTIN J. RICHARD, OF RAYNE, LOUISIANA.

HARROW.

1,134,639.

Specification of Letters Patent.

Patented Apr. 6, 1915.

Application filed November 2, 1914. Serial No. 869,851.

To all whom it may concern:

Be it known that I, MARTIN J. RICHARD, a citizen of the United States, residing at Rayne, in the parish of Acadia and State of Louisiana, have invented certain new and useful Improvements in Harrows, of which the following is a specification, reference being had to the accompanying drawings.

This invention relates to certain improvements in harrows, and an object of the invention is to provide a novel and improved device wherein the ground engaging members of the harrow are caused to travel in a circular path as the device is drawn over the ground.

The invention consists in the details of construction and in the combination and arrangement of the several parts of my improved harrow whereby certain important advantages are attained and the device is rendered simpler, less expensive and otherwise more convenient and advantageous for use, all as will be hereinafter fully set forth.

The novel features of the invention will be carefully defined in the appended claim.

In order that my invention may be the better understood, I will now proceed to describe the same with reference to the accompanying drawings, wherein—

Figure 1 is a view in top plan of a harrow constructed in accordance with an embodiment of my invention; Fig. 2 is a transverse vertical sectional view taken through Fig. 1; and Fig. 3 is an enlarged fragmentary view in perspective of one of the spoke members herein included.

As disclosed in the accompanying drawings, 1 denotes a beam provided at one extremity with the means 2 whereby draft rigging may be suitably engaged in order that the device may be drawn over the ground, and disposed vertically through the beam at a predetermined point intermediate thereof is a shaft 3 around which is adapted to rotate the hub plate 4. Surrounding the hub plate 4 and in spaced relation thereto is the annular member 5 substantially Z-shape in cross section, with the upper flange of which is adapted to contact the gage wheel 7 mounted on the outer extremity of the arm 8 operatively engaged as indicated at 9 with a side face of the beam 1. I have found in practice that it is particularly advantageous to have the draft portion of the wheel 7 oval in cross section, as it is believed

to be clearly shown in the drawings forming a part hereof. The arm 8 has adjustably mounted thereon the member 10 of a predetermined weight whereby it will be perceived that the action of the gage wheel 7 upon the upper flange 6 may be operatively regulated. In order to maintain the member 10 in its varying adjusted positions, I dispose therethrough the clamping member 11 herein disclosed as a conventional set screw adapted to coact with the arm 8 in a conventional manner.

The annular member 5 is operatively tied or connected with the hub plate 4 through the medium of the radiating spokes 12 formed of angle iron and secured to the lower flange 14 of the member 5 and such spokes 12 are provided longitudinally thereof with the spaced openings 15 positioned in close proximity to the upstanding flange 16 of the spokes and through which are adapted to be directed the shanks 17 of the ground engaging members 18, as is believed to be self-evident. The base flange 19 of the annular member 5 is also provided with spaced openings 20 positioned in close proximity to the vertical portion 21 thereof, and through which are adapted to be projected the shanks 22 of the additional ground engaging members 23. By having the ground engaging members 18 and 23 arranged as herein described, I have found in actual practice that the ground over which my improved harrow is drawn is effectively treated. The extremity of the beam 1 opposite that provided with the engaging means 2 is provided with a stub shaft 24 on which is mounted the wheel 25 which is adapted to ride upon the upper flange 6, as is believed to be fully set forth in the accompanying drawings.

From the foregoing description it is thought to be obvious that a harrow constructed in accordance with my invention is of an extremely simple and comparatively inexpensive nature, and is particularly well adapted for use by reason of the convenience and facility with which it may be assembled and by reason of the effectiveness with which it performs its functions, and it will also be obvious that my invention is susceptible of some change and modification without material departure from the principles and spirit thereof and for this reason I do not wish to be understood as limiting myself to

the precise arrangement and formation of the several parts herein shown of my invention in practice.

I claim:

- 5 A harrow of the class described comprising a beam, a vertically disposed shaft carried thereby, a hub plate rotatably mounted upon the shaft, an annular member surrounding the hub plate and in spaced relation thereto, 10 said annular member being substantially Z-shape in cross section, spokes radiating from the hub plate and operatively engaged with the base flange of the annular member, each of said spokes being substantially L-shape 15 in cross section and provided with longitudinally spaced perforations in the base flange in close proximity to the upstanding flange, the base flange of the annular member being also provided with spaced perforations in

close proximity to the vertical portion thereof, a wheel operatively supported by one extremity of the beam and adapted to contact with the upper flange of the annular member, an arm operatively engaged with the beam, a wheel mounted upon said arm and 25 adapted to travel upon the upper flange of the annular member, a weighted member adjustably supported upon the arm, and ground engaging members engaged with the annular member and the spokes and disposed 30 through the openings therein.

In testimony whereof I hereunto affix my signature in the presence of two witnesses.

MARTIN J. RICHARD.
